Primary Examiner—Mimosa De*(74) Attorney, Agent, or Firm*—McDermott Will & Emery LLP**CLAIM**

We claim the ornamental design for a chair back, as shown and described.

DESCRIPTION

FIG. 1 is a front perspective view of a chair back according to the new design; and,

FIG. 2 is a rear perspective view of a chair back shown in FIG. 1.

In the drawings, the broken lines form no part of the claimed design.
